UNITED STATES PATENT OFFICE

JACQUE C. MORRELL AND JESSE L. ESSEX, OF CHICAGO, ILLINOIS, ASSIGNEES TO
UNIVERSAL OIL PRODUCTS COMPANY, OF CHICAGO, ILLINOIS, A CORPORATION OF
SOUTH DAKOTA

REFINING OF HYDROCARBON OIL

No Drawing.

Application filed January 9, 1928. Serial No. 245,625.

This invention relates to refining of hydrocarbon oils and refers more particularly to the purification or refining of cracked distillates for the purpose of removing therefrom 5 objectionable and deleterious compounds which are present therein or may be formed as a result of the commercial use thereof.

In its broad aspects, the present invention is directed to the treatment of cracked distillates produced from liquid phase, liquid-vapor phase, or vapor phase cracking processes, while in its specific aspects it is particularly adapted to the refining of cracked distillates produced in the vapor phase cracking of hydrocarbons.

It is known that cracked distillates obtained in the vapor phase cracking of hydrocarbons contain compounds which form in excessively large amounts gummy compounds 20 and oily polymers when used, for instance, in an internal combustion engine as motor fuel.

It is a principal object of the present invention to provide a process for removing those compounds which are gummy in themselves or form gummy compounds or oily polymers when used. It is a further object to produce this result economically and efficiently.

30 It is a still further object of the invention to produce a product characterized by its stability, absence of color forming and odor forming compounds, and free from objectionable amounts of gum forming or polymer forming compounds.

In the specific embodiment of the present invention we propose to subject cracked distillates to the action of borax, either dry or in solution. In carrying out the process the 40 borax is introduced into the cracked distillate and the entire mixture subjected to heat. The manner of heating may be by prolonged refluxing, by distilling while refluxing, or by distilling the oil over the borax. In short, 45 the time of heating the oil in the presence of the borax is regulated to suit the type of oil undergoing treatment, and the results desired in the refining action and reduction in amount of deleterious substances. As an 50 illustration, it has been observed that oils

undergoing this treatment, for example, cracked distillates from vapor phase cracking of hydrocarbons, have been reduced in gum content to as low as 3% to 10% of the original gum content, for example, cracked 55 distillates containing a gum content of 3,000 milligrams per 100 cc's. have been reduced to approximately 100 milligrams per 100 cc's.

The refining agent contemplated for use with the present invention, i. e. borax, may 60 be used as a sole refining agent or may be used as a step in refining in conjunction with usual refining agents such as sulphuric acid, caustic soda, sodium plumbite, adsorbent material and the like.

We claim as our invention:

1. A step in a process of refining cracked hydrocarbon distillate which consists in subjecting said distillate to the action of borax at a temperature substantially above atmospheric but below cracking to remove therefrom gummy compounds and oily polymers.

2. A step in the process of refining cracked hydrocarbon distillates obtained by vapor phase cracking of hydrocarbon oils, which 75 consists in subjecting such distillate to the action of borax at a temperature substantially above atmospheric but below cracking to remove gummy compounds and oily polymers therefrom.
